2,626,534

DIAMOND BORING MACHINE

Merton H. Arms and Leon J. Barnard, Springfield, Vt., assignors to Bryant Chucking Grinder Company, Springfield, Vt., a corporation of Vermont

Application September 30, 1947, Serial No. 776,892

8 Claims. (Cl. 77—3)

1

This invention relates to diamond boring machines, and has for one object to provide improved means for relieving the tool from the work preparatory to withdrawing it so that the surface of the bored hole shall not be scored as the tool is withdrawn.

A further object is to provide for stopping the rotation of the boring tool or tools at a predetermined angular position preceded by a slowing of its or their rotation.

Still another object is to provide hydraulic means for producing the rotation of a boring tool and its slowing before stopping at the predetermined angular position.

A further object is to improve the carriage mounting.

Further objects and advantages will appear from a description of embodiments of the invention shown in the accompanying drawings in which

Figure 1 is a front elevational view of a boring machine embodying the invention.

Figure 2 is a fragmentary view to a larger scale partly in front elevation and partly in vertical section.

Figures 3, 4 and 8 are detail sectional views on the correspondingly numbered section lines of Figure 2.

Figure 5 is a detail sectional view through the boring bar and the work adjacent to the tool.

Figure 6 is a detail sectional view on line 6—6 of Figure 3.

Figure 7 is a detail sectional view on line 7—7 of Figure 6.

Figure 9 is a fragmentary view partly in elevation and partly broken away showing a modification.

Figure 10 is a diagrammatic view of the hydraulic system of the machine for rotating the tool bar and for relieving it for withdrawal.

Figure 11 is a fragmentary front elevation of a boring machine showing a modification.

Referring first to Figures 1 to 7, the boring machine comprises a bed 1 having a pair of spaced side members 2 and 3. The top member 4 joins the side members 2 and 3, and between these side members and nearer to the member 2 than the member 3, this top member is provided with a pair of spaced half cylindrical bearings 5 supporting a bar 6 circular in cross section.

This bar 6, as shown best in Figures 1 and 2, supports on its ends a pair of hydraulic cylinders 7. The cylinders 7 are suitably secured somewhat flexibly by plates 7a at the ends of the machine, the plates taking the end thrust from

2

the cylinders, and the bar 6 acts as a hydraulic plunger which is moved axially by the introduction and discharge of hydraulic fluid into the outer ends of the cylinders 7, as through ports 8.

5 An adjustable stop 9 is threaded through a stem 10 having a flange 11 at its outer end secured to the head of each cylinder, as by screws 12, and this stop may contact with an abutment 13 seated at the base of a socket 14 in the adjacent end of the bar 6. Impingement of the abutment 13 on the stop 9 limits the inward motion of the bar 6 within each of the cylinders 7. The stop 9 may be accessible for adjustment through the outer end of the stem 10, and a pipe plug 15 threaded into the outer end of this stem normally holds the abutment 9 inaccessible for adjustment and prevents leakage escaping from the stem 10. However, when necessary, the plug 15 may be removed. In order to take up lost motion 10 in the stop adjustment, the inner end of the stem 10 may be transversely slotted as at 16 to form a tongue 17 which may be flexed toward the main portion of the stem as by turning a screw 18 passed therethrough and threaded into the stem.

15 The bar 6 supports a carriage 20, the carriage 20 being secured to the bar at intervals as by screws 21 (see Figure 2). The bar 6 is rockable as well as axially movable in the cylinders 7 and its angular position and the consequent angular position of the carriage 20 may be determined by 20 a shoe 22 (see Figure 3) adjustably secured to a vertical side face 23 of the carriage and which is supported on the upper edge of a bar 24 which is also secured for vertical angular adjustment to the adjacent side face of the bed 1 as by a plurality of screws 25 passing through enlarged holes 26 through the bar 24 and threaded into the base 1. Preferably, for smoothness of operation, the shoe 22 rests upon a series of antifriction rolls 30 supported in a case 31 and resting upon the 25 upper edge of the bar 24. By reason of this construction, it is an easy matter to adjust the bar 24 so that the carriage 20 may be moved in a true rectilinear path regardless of any warping of the bed 1 which may occur as the machine ages or it may be rocked as it moves axially of the bar 6. This latter adjustment permits boring of a round hole at an angle to the axis of the bar 6.

30 Arching over the carriage 20 is a bridge 32 which is secured at its outer edges on the upper 40 faces of the side frames 2 and 3. Two of these bridges are shown in Figure 1, one at each end of the machine, and bridging over opposite end portions of the carriage 20. The carriage and the bridge support the work to be bored and the 45

boring tool, respectively, and as shown, the carriage 20 supports a work holder 35 while the bridges 32 have secured thereto the non-rotating tool holders 36. This is the more usual arrangement, although occasionally the work may be held by the bridge and the tool by the carriage, and a further modification is shown in Figure 11 which will be further described herein. The work holder 35 supports a work carrier 37 within which is fixedly mounted a work piece 38 which is to be bored.

Each of the tool carriers 36 carries a motor indicated generally at 40, and arranged in rotary driving relation to a rotary shaft 41 which constitutes the boring bar and carries a boring tool 42 projecting laterally therefrom adjacent to its free end. The type of motor 40 shown herein is a well known type of hydraulic motor and the speed of each of these motors may be determined by a control mechanism at the back of the machine, similar to that at 45 on the forward face of the machine, in accordance with a predetermined cycle, depending upon the axial position of the carriage 20, as through a plurality of cams similar to the cams 46, carried by the carriage and having their lower edges impinging upon a hydraulic control mechanism indicated by the throttle valve 47 of Figure 10. The control mechanism 45 and the cams 46 control the table motion and limit switches for hydraulic motor control. This arrangement of hydraulic motors and controls for actuating the motors 40 and for controlling the admission and discharge of hydraulic fluid with respect to the traversing cylinders 7 is old and well known and per se forms no part of the present invention. However, it is believed that the mounting of the carriage and the control of the motors for slowing the rotation of the boring bars and stopping them at a desired angular position, together with the mechanism for relieving the boring tools so that when they are removed from the work they do not score it, are novel.

Means are provided by which, when the boring bar or bars is stationary and with the boring tool or tools in a desired angular position, some portion of the machine is sprung in such a manner as to retract the tool or tools radially from the work face. This is done when the respective tool has performed the boring operation and is about to be pulled back through the work and is for the purpose of laterally retracting the tool from the work face so that during the retirement of the tool it does not score the work face. Two methods of accomplishing this are shown herein.

Referring first to Figures 1, 2, 3 and 4, at one side of the machine there is fulcrumed a lever 50. As shown best in Figure 4, this may be fulcrumed on one of the side frames, as 3, on a bolt 51 which passes through a spherical enlargement 52 on the inner face of the lever 50 and is threaded into the wall member 3, there being a clearance around the shank of the bolt 51 for a considerable portion of the thickness of the spherical portions 52. The upper end of this lever 50 has an adjustable abutment 53 which bears against the side of the bridge 32 toward its upper end. This abutment 53 may be threaded through the lever 50 for purpose of adjustment. The lower end of the lever 50 has bearing on its inner face the rounded outer end of a piston rod 54 having a piston 55 at its inner end riding within a hydraulic cylinder 56. It will be evident that by forcing the piston 55 outwardly, the lever 50 may be rocked about its

pivotal connection with the frame 3 and its upper end pressed against one end of the bridge 32 with sufficient force to deflect this bridge so as to swing the tool carrier 36 laterally so that if the tool 42 is arranged in a horizontal plane, and turned toward the lever 50, this deflection of the bridge will serve to retract the tool 42 out of contact with the inner face of the work piece as shown by dotted lines in Figure 5. When hydraulic pressure is released from the left hand end of the cylinder 56, allowing the lever 50 to resume an unstressed condition, the natural spring of the bridge will return it to normal position.

In Figure 9 there is shown another means for springing the tool away from the work face, this means acting upon the tool bar itself and springing the outer end of the tool bar out of its normal coaxial relation with its inner portion. With this arrangement the tool bar 41 is provided with a circular flange 62 outwardly of a bearing 60, the outer portion of which is formed with a shoulder portion 64 with which cooperates a guard 65 to tend to prevent entry of foreign matter, such as chips, or the like, behind the flange 62.

A rod 66 is mounted for axial motion through spaced bearing portions 67 and 68 of the casing 61 and is normally held retracted out of contact with the flange 62, as by a coil spring 69 bearing between the rear face of the bearing 67 and a collar 70 secured to the rod 66. The opposite end of this rod 66 extends into a hydraulic cylinder portion 71 and may be impinged upon by a plunger 72 slidably guided therein. By introducing fluid pressure within the cylinder 71 to the left of the plunger 22, this plunger 22 is forced against the end of the rod 66, which, in turn, is forced against the flange 62 eccentric to the axis of the boring bar 41. This acts to bend the boring bar 41 about the bearing 60, as shown in dotted lines, in a direction to retract the tool 42 radially from the work when it is stationary in the proper angular position. When the fluid under pressure is discharged from the left hand end of the cylinder 71, the rod 66 is pushed back by the spring 69 away from the flange 62 and allows the boring bar to resume its unstressed condition which would bring the tool 42 into position to bore the work. The cylinder 71 is also provided with a piston 75 normally projected into the cylinder, as by a coil spring 76. When the fluid under pressure is admitted to the left hand end of the cylinder 71 through the pipe 74 to force the plunger 72 to the right and deflect the boring tool out of normal position, it also acts on the piston 75, pressing it to the left and actuating a stop switch at 77. The actuation of this stop switch may serve to control a valve which reverses the direction of traverse, thus withdrawing the boring tool from the work.

In Figures 8 and 10 there is illustrated the mechanism for slowing down and stopping the rotation of the boring tool at a predetermined angular position, and for deflecting the boring tool out of its normal position so that it may be withdrawn without scoring the work. This mechanism is shown as applied to one of the hydraulic motors 40 and when there are a plurality of such motors, such a mechanism would be employed for each. At 100 is shown a fluid tank from which fluid is withdrawn by two pumps 101 and 102. The pump 101 is of much larger capacity than the pump 102 and pumps at a higher pressure, such pressures being determined by the relief valve 1010 and 1020, respectively.

During the normal rotation of the boring bar, pressure from the pump 101 passes through a pipe 103 to a valve casing 104 and acts upon one end of a valve plunger 105, driving it to the left against the action of a spring 106 and opening communication between a chamber 107 and a chamber 108. From this latter chamber, fluid under pressure passes through the pipes 109, 110 and 111 to the hydraulic motor 40, the discharge from this motor passing through the pipe 112, past a valve 113, through a pipe 114 back to the drain pipe 115. The motor is now operating at its fast boring speed. The valve 113 is held open by pressure from the high pressure line 111, passing beneath it and holding it open against the force of a compression spring 115. Pressure from the chamber 107 of the valve casing 104 passes the check valve 120 and the port and pipe 121 to the upper end of a valve chamber 122 where it acts upon the upper end of a piston valve 123 and holds it depressed against the action of a spring 124 which tends to lift it. This position of the parts is shown in Figure 8.

The valve 123 has a pin and slot connection 125 with a lever 130 fulcrumed at 131 and having a cam follower roll 132, which, when the valve 123 is in its downward limit of motion, is held out of contact with an edge cam 134 keyed to the shaft 41. This edge cam 134 has a notch 135 at one part of its periphery, one side of the notch being outwardly extended to form a stop lug 136.

When the boring has been nearly completed, a valve 140 (see Figure 10) is opened to permit the discharge of the high pressure high capacity pump 101 directly back to the tank 100 through the pipe 142. This immediately releases the pressure in the pipe 103, allowing the valve 105 to move to the position shown in Figure 10 which shuts off the high pressure from the chamber 107 to the chamber 108. The pressure in the chamber 107 also is relieved so that the pressure in the line 121 bleeds off past the needle valve 145, allowing the spring 124 to lift the valve from the position of Figure 8 to that approaching the position of Figure 10, the follower roll 132 riding on the periphery of the cam 134 spaced from the notch 135. This causes the valve 123 to open a communication from the pipe 150, which receives pressure from the low capacity low pressure pump 102, into the cannelure 151 of the valve 123 through a longitudinal valve passage 152 out through a cannelure 153 of this valve, past the check valve 154 and into the pipe 110. From this pipe 110 it reaches the motor 40 through the pipe 111 but as the pump 102 has a relatively small capacity and low pressure, the motor is driven at a relatively slow speed.

In this position of the valve 123, the follower roll 132 is riding on the periphery of the cam 134 and as soon as the notch 135 comes opposite to this follower, the follower is allowed to rise into it as shown in Figure 10. This permits the valve 123 to be lifted a little further, cutting off the cannelure 153 from the check valve 154, thus cutting off the supply of hydraulic fluid from the pump 102 to the motor 40. At the same time a second cannelure 168 of the valve 123 opens communication to the passage 161 from the passage 153, the passage 161 leading to the mechanism for springing the tool out from the work. As shown in Figure 10 this comprises the hydraulic cylinder 56 by which the bridge is sprung. If desired, of course, this could be, instead of the cylinder 56, the cylinder 11 of Figure 9, in which case the

boring bar or shaft would be deflected to retract the tool.

As the cam follower roll 132 is carried into the notch 135, the stop shoulder 136 contacts with this roll and tends to prevent further turning of the shaft 41. Should the stop shoulder be close to the roll 132 when the valve 140 is opened, this shoulder may ride by, but when it comes around a second time it will stop. The low pressure is preferably sufficiently low so that the motor would stall at this time even though the fluid were not cut off. Thus the power to the driving motor is cut off and the rotation of the shaft is stopped. In this position of the parts, also, the pressure in the pipe 110 being cut off, the spring 115 of the valve 113 closes this valve and shuts off the discharge from the motor 40, thus hydraulically locking the motor in stationary position. The notch 135 is so angularly related to the tool carried by the shaft 41 that when the rotation of this shaft is stopped, the tool is in such angular position that the springing of the bridge or the springing of the tool shaft retracts the tool from the work face so that when it is withdrawn from the work it does not score this face.

In some cases it may be found convenient to rotate the work, in which case the boring bar may be non-rotating. Such a construction is shown in Figure 11 where the work piece 200 is carried in a chuck 201 rotatably mounted in the bridge and rotated by a motor such as the hydraulic motor 40 heretofore mentioned. The boring bar 202 is then non-rotatably mounted on the carriage 20. With this arrangement no means need be provided for stopping the rotating parts in any particular angular position. The boring tool may be retracted from the work either by deflecting the bridge as heretofore described, in which case the boring tool is fixed to project from the boring bar in the general direction of deflection of the bridge, or the bar itself may be sprung backwardly relative to the direction of projection of the tool therefrom, as by exerting eccentric pressure lengthwise thereon after the manner shown in Figure 9 as heretofore described.

From the foregoing description of certain embodiments of this invention, it should be evident to those skilled in the art that various further changes and modifications might be made without departing from its spirit or scope.

We claim:

1. A boring machine comprising a base, parts one of which comprises a carriage mounted for reciprocation on said base and the other of which comprises a bridge carried by said base and extending over said carriage, a shaft journaled on one of said parts and extending in the direction of motion of said carriage, a work support carried by the other of said parts, a boring tool carried by said shaft, power means for rotating said shaft, means controlling said power means to first slow the rotation of said shaft to a predetermined low speed and then stop such rotation from said low speed with said tool in a predetermined angular position, and power means controlled by said controlling means for thereupon springing the part carrying said tool in a direction to retract said tool radially from the work.

2. A boring machine comprising a base, a carriage mounted for reciprocation on said base, a bridge carried by said base and extending over said carriage, a shaft journaled on said bridge and extending in the direction of motion of said carriage, a work support carried by said carriage,

a boring tool carried by said shaft, power means for rotating said tool, means controlling said power means to first slow the rotation of said shaft to a predetermined low speed and then stop such rotation from said low speed with said tool in a predetermined angular position, and power means controlled by said controlling means for thereupon springing said shaft in a direction to retract said tool radially from the work at the stopped position.

3. A boring machine comprising a base, parts one of which comprises a carriage mounted for reciprocation on said base, and another of which comprises a bridge supported on said base and relative to which said carriage is movable, a work holder carried by one of said parts, a shaft journaled lengthwise of the direction of motion of said carriage on the other of said parts, a hydraulic motor for rotating said shaft, a boring tool carried by said shaft for operating on work carried by said work holder, two sources of fluid pressure one of greater capacity and pressure than the other, valve means selecting the source effective to actuate said motor, means actuating said valve to switch from the greater capacity to the smaller capacity source near to the end of a boring operation to thereby slow the rate of rotation of said shaft to a predetermined low speed, stop means to thereafter stop the rotation of said shaft from said low speed with said tool in a predetermined angular position, means for springing said tool radially away from said stopped position when in said position out of contact with the work, and means actuated by said stopping means when in stopped position to connect one of said sources to said springing means.

4. A boring machine comprising a base, parts one of which comprises a carriage mounted for reciprocation on said base, and another of which is supported on said base and relative to which said carriage is movable, a work holder carried by one of said parts, a shaft journaled lengthwise of the direction of motion of said carriage on the other of said parts, a hydraulic motor for rotating said shaft, a boring tool carried by said shaft for operating on work carried by said work holder, two sources of fluid pressure one of greater capacity and pressure than the other, valve means selecting the source effective to actuate said motor, means actuating said valve to switch from the greater capacity to the smaller capacity source near to the end of a boring operation to thereby slow the rate of rotation of said shaft, a cam carried by said shaft and having on its periphery a stop lug and a notch adjacent to said lug, a lever having an arm connected to said valve and a follower roll bearing on said periphery only when said valve is in position to connect said source of smaller capacity to said motor and to then be in position to engage said stop lug to stop the rotation of said tool in a definite predetermined angular position and to engage in said notch, means for springing said tool in a direction relative to its stopped angular position to move the tool out of contact with the work, said valve being moved by such notch engagement to shut off both sources from said motor and to connect one of said sources to said springing means to spring said tool radially away from the work.

5. In a boring machine, a boring bar, a support for said bar, a boring tool carried by said bar spaced from said support, a flange on said bar spaced from said support, and a power

pressed element bearing on one face of said flange eccentric to said bar for springing said bar and tool laterally relative to said support to move said tool back from boring position

5 when said tool extends toward said element, said means supporting said element nonrotatable with said bar.

6. In a boring machine, a rotary boring bar, a motor connected to rotate said bar, said bar being unsupported for a substantial portion of its length, a boring tool carried by said bar in its unsupported portion, a flange on said bar at said unsupported portion, a plunger substantially parallel to said bar and engaging said

15 flange, means supporting said plunger non-rotatable with said bar, means for stopping the rotation of said bar in angular position with said tool projecting toward said plunger, and means for pushing said plunger against said flange to thereby spring said tool backwardly.

7. A boring machine comprising a base having a pair of spaced side walls, a cylindrical bar mounted for axial and angular motion on said base between said side walls and nearer to one 25 of said walls than to the other, a carriage member fixed to said bar, a guide bar adjustably fixed to said base inwardly of and adjacent to the other of said side walls and adjustable angularly vertically, a shoe carried by said carriage member and supported on said guide bar whereby said carriage may rock during its motion axially of said bar, a bridge member supported on said side walls and beneath which said carriage member may extend, a work support carried by 30 one of said members, and a tool on the other of said members for operating on work carried by said work support.

8. A boring machine comprising a base having a pair of spaced side walls, a cylindrical bar 40 mounted for axial and angular motion on said base between said side walls and nearer to one of said walls than to the other, hydraulic cylinders carried by said base and into which the ends of said bar extend to form pistons therefor, means for controlling supply and discharge 45 of hydraulic pressure to and from said cylinders to reciprocate said bar, a carriage member fixed to said bar, a guide bar adjustably fixed to said base adjacent to the other of said side walls for vertical angular adjustment, a shoe carried by said carriage member and supported on said side walls and beneath which said carriage member may extend, a work support carried by one 50 of said members, and a tool on the other of said members for operating on work carried by said work support.
